CLAIM

The ornamental design for a golf shoe, as shown and described.

DESCRIPTION

FIG. 1 is a top front perspective view of a golf shoe, showing my new design;

FIG. 2 is a top plan view of FIG. 1;

FIG. 3 is a bottom view of FIG. 2;

FIG. 4 is a left side elevational view of FIG. 1;

FIG. 5 is a right side elevational view of FIG. 1;

FIG. 6 is a front elevational view of FIG. 1; and,

FIG. 7 is a rear elevational view of FIG. 1.

The phantom lines shown in FIGS. 1, 2, 4, 5 and 6 form no part of the claimed design.
